WILLIAM S. LEE, RICHARD PFAEHLER, AND DAVID NABOW, OF CHARLOTTE,
NORTH CAROLINA

HYDRAULIC GATE-OPERATING MECHANISM

Application filed September 24, 1927. Serial No. 221,717.

This invention is an improvement in chain hoists for operating head gates, and more particularly in devices of the character in question for operating head gates of the butterfly or pivot type used for the closure of large passage ways.

Head gates, such as are used in the pen stocks and turbine flumes of hydro-electric power developments are of large size and subjected in normal conditions of use to a considerable water pressure, which is greatly increased in certain emergencies.

Normally the gate is operated with the pen stock filled with water, which exerts a back pressure on the gate. In case however, of a run away of the turbine, when the head gate nears its closed position, a relatively small quantity of water will flow through the gap between the gate and the passage way, and this small quantity quickly drains away through the open turbine wicket gates, with a resulting lack of back pressure on the gate.

A more severe lack of balance between the pressure on the opposite faces of the gate occurs when for instance the head gate strikes an obstruction near its closed position, and the gate is again opened without filling the empty pen stock through a by-pass. In either case the unbalanced pressure greatly increases the strain upon the operating mechanism for the gate.

It is frequently desirable to use two head gates in one pen stock intake, in order to care for the large quantities of water in large turbine installations, such as occur in modern water power practice. In such case it is desirable to operate the head gates substantially simultaneously, that is to open and close the gates at the same time, though not necessarily in complete coincidence so far as concerns the commencement and completion of the operation.

One of the primary objects of the present invention is the provision of a hoist of simple construction, with no delicate parts under water, and which will be entirely capable of operating the gate not only under normal operating conditions, but also in case of emergencies such as above referred to.

50 A further object is the provision of an in-

stallation for simultaneously opening and closing a plurality of head gates, and so arranged that while operated at the same time the gates may be out of phase in their opening or closing movement.

Another object is the provision in such an installation of mechanism, manually operable for opening or closing the gates in case of emergency, or for completing the closing of either gate when the gates are operated 60 out of phase.

Another object is the provision of mechanism in connection with the installation for preventing damage to the parts through over movement of the operating mechanism, controlled by the movement of the said mechanism.

With these and other objects in view the invention consists in the construction and novel combination of parts fully described 70 hereinafter, illustrated in the accompanying drawings, and pointed out in the claims appended hereto, it being understood that various changes in the form, proportion, size and minor details of construction within the scope 75 of the claims, may be resorted to without departing from the spirit of the invention.

In the drawings forming a part hereof: Fig. 1 is a vertical section through the pen stock intake of an installation provided with 80 the improved gate operating mechanism.

Fig. 2 is a plan view.

Fig. 3 is an enlarged view of the hoisting mechanism.

Fig. 4 is a section on the line 4—4 of Fig. 5. 85

Fig. 5 is a partial front elevation in detail of the operating shaft.

Fig. 6 is a diagram of the wiring.

In the present embodiment of the invention, the gate is of the type shown and described in application Serial No. 741,575, filed on October 4, 1924, now Patent No. 1,642,253, issued September 13, 1927 composed of a central section or axis 1, and lateral wings 2 and 3 secured to the axis, which in practice is of cast steel with bronze bushed trunnions 4 at its ends, while the lateral sections may be of cast iron. The lateral sections are connected to the axis by mechanism indicated at 5 and 6 respectively at the op- 100

posite faces of the gate, the mechanism 5 in the present instance being exterior of the gate, while the mechanism 6 is interior.

The gate is arranged in the intake 7, the 5 trunnions 4 being journaled in the walls thereof, and when closed, as shown in full lines in Fig. 1, the intake is completely closed, and the gate is substantially perpendicular to the direction of flow. When the 10 gate is opened as indicated in dotted lines in the same figure, it is parallel with the direction of flow.

An air vent 8 is provided below the gate, and a by-pass indicated at 9. This by-pass 15 is controlled by a gate 10 above the head gate, having guided movement in a frame 11, and operated to open and closed position, by mechanism indicated generally at 12. By means of the by-pass water may be admitted 20 below the gate as clearly shown.

The gate is opened and closed by means of a sprocket chain 13, one end of which is connected to the gate below the axis by means of a rod 14. A rod 15 is connected with the 25 gate above the axis, and the rod is connected to the other end of the chain by a link 16, having interposed in the length thereof a turn-buckle 17, by means of which the effective length of the link 16 may be varied. The 30 chain passes over a sprocket wheel 18 on a shaft 19 journaled on an axis parallel with the axis of the gate. The shaft is supported in bearing pedestals 20.

When the installation includes two gates, 35 as shown in the present instance, a second shaft 19^a is supported in alignment with the shaft 19, in similar pedestals 20^a, and the shaft is provided with a sprocket wheel 18^a, over which passes a sprocket chain 13^a, connected with the second gate in the same manner as the sprocket chain 13 is connected with the first gate. A gear wheel 21 is supported between the shafts and the wheel is adapted to be connected with either or both, by means 40 of clutches indicated generally at 22 and 22^a respectively. Each of these clutches includes a fixed part on the shaft 19 or 19^a as the case may be, and a movable part cooperating with the fixed part to connect the shaft 19 or 19^a with the gear wheel 21, and the 45 movable parts are operated by mechanism to be described.

The wheel 21 is driven by a worm 23, on a worm shaft 24 arranged at right angles to the shafts 19 and 19^a. The worm shaft is provided at the end remote from the worm with a gear wheel 25 meshing with a pinion 26 on a counter shaft 27 arranged parallel with the shaft 24. The counter shaft has a 50 gear wheel 28 meshing with a pinion 29 on the shaft 30 of a suitable motor 31, in the present instance an electric motor. The gear train 25, 26, 28 and 29 provides a reducing train between the shafts 30 and 24, and the 55 relative speed of shaft 24 and shafts 19 and

19^a is further reduced by the worm and gear connection 21—23. Each of the clutches 22 and 22^a is operated by means of a lever 32. The lever is pivoted intermediate its ends as shown, one end being connected with the movable member of the clutch, while the other end is provided with a nut 33 moving on a screw shaft 34 journaled parallel with the shaft 19 or 19^a, and having a hand wheel 35 for convenience in manipulating the screw shaft. 75

The motor shaft 30 is provided with a gear wheel 36 meshing with another gear 37 on a shaft 38 parallel with the motor shaft. The wheel 36 is normally loose on the motor shaft, but may be connected thereto when desired by the clutch mechanism indicated at 39. The shaft 38 has a worm wheel 40, which is engaged by a worm 41 on a worm shaft 42 having a hand wheel 43. 80

When it is desired to operate the gates manually the gear wheel 36 is connected to the motor shaft by the clutch 39. When so connected, by means of the hand wheel 43 the shaft 41 may be turned, and through the clutches 22—22^a, either or both shafts 19 and 19^a may be turned. Normally the clutches 22 and 22^a are arranged to connect the gear wheel 21 with the shafts 19 and 19^a, and the parts are so positioned that the gates will 85 be operated simultaneously. In case of emergency or for any other reason, one gate may be released and the other operated.

Each shaft 19 and 19^a may be connected to a shaft 44 by means of the chain speed 90 reducing gear indicated at 45. The shaft 44 operates a limit switch 46 of usual construction, and also a position indicator indicated at 47, through the gear connection 48. The position indicator is also of usual construction, having a movable indicator for indicating the position of the gate. 105

By connecting the limit switches 46 in parallel, the circuit breaker for the motor 31 will be tripped, and the hoisting operation stopped, as soon as contact is established by one of the two limit switches at the opened or closed position of either gate, when the gates are operated simultaneously. If gate I only is operated by throwing in the clutch 22, or by releasing the clutch 22^a, the limit switch of shaft 19 will be caused to trip the circuit breaker for the motor at the opened or closed position of gate I. In a similar manner the limit switch of shaft 19^a will trip 115 the circuit breaker for the motor at the opened or closed position of gate II, when gate II is operated alone.

Should for any reason the limit switches 125 fail to operate, the slack provided in the sprocket chains 13 and 13^a, which is usually about 4 inches, will be taken up as soon as the gates have reached the closed position, or have over traveled the open position. Assuming that gate I is brought to closed posi- 130

tion, with the motor still in operation, and the chain slack entirely taken up due to the failure of the operation of the appropriate limit switch, the rod or chain connected to gate I will be subject to tension, and will gradually create the necessary overload, causing tripping of the overload release switch provided for the motor, it being understood that the motor is of the overload release type.

Assuming gate I to have reached the position of over travel after full opening, with the motor still in operation, due to failure of operation of the appropriate limit switch, the rod of the chain connected to the gate below the axis will be subject to tension, and will thus cause a tripping of the overload release switch for the motor. Both of the chains 13 and 13^a are designed to withstand a stress higher than the extreme overload properties of the motor require before the elastic limit of the material is reached.

Referring to Fig. 2, it will be noticed that the connections indicated at 50 and 51 between the rods 14—15 and the gate are located near to and on either side of the partition wall 52 between the gates. This arrangement enables a minimum length of the heavy main shafts 19 and 19^a. It is obvious, however, that the said connections may be at any desired points on the gates.

If desired, by means of the turnbuckles 17, one gate may be set slightly in advance of the other, as far as regards opening. With this arrangement, when the gates are to be opened, gate I for instance, will open slightly in advance of gate II, so that the entire load is brought upon the motor in successive increments. That is the inertia of gate I will have been overcome, before the motor is called upon to overcome the inertia of gate II.

Such arrangement will also result in the starting of gate II to closed position before gate I is started. The arrangement is enabled by shortening of the connection 15—16 between the upper side of one gate and the sprocket chain. When the gates are so set, that is with gate I slightly in advance of gate II in the opening movement, the motor may be stopped when gate II is fully closed, and gate I may be closed by the hand operated mechanism.

The final closure of one or both gates may be made by means of the hand operating device, the limit switches being set to trip the motor circuit breaker before the gate or gates are seated. By this arrangement possible slamming of the gate is prevented. The worm 23 which drives the wheel 21 will act as a brake to hold the gates in the desired position of opening when the motor 31 is not in operation.

Normally the clutches 22 and 22^a only can be released when one or all of the gates are in closed position. With a gate open or partially open the water pressure tending to close

the same is so great that the force exerted by the movable part of the clutch 22 or 22^a against the fixed part is such that a shift of considerable size is necessary to release the clutch. In order to block any gate in any desired open position, and to release the clutch under no pressure, the mechanism shown in detail in Figs. 4 and 5 is provided.

In this mechanism a toothed shoe 55 is anchored to the masonry 56 near a wheel 53 keyed to the shaft and movable longitudinally thereof, and in position to be engaged thereby when the wheel is shifted laterally by the clutch 54. When the wheel 53 is so shifted and engaged with the shoe, the gate may be manually operated to release the pressure between the movable and the fixed parts of the clutch, this pressure being transferred to the teeth of the shoe 55, after which the clutch 22 or 22^a may be released under no pressure by means of the shifting device 32.

A latching device is provided for holding the gate in a given position, and to support the chain 13 in case the sprocket wheel 18 and shaft 19 are removed for inspection, or during repair work. This device includes a latch member 57, which is passed through a link of the chain and is adapted to rest at each end on cross bars 58. A latch may be provided for the chain on each side of the wheel, as shown.

What is claimed as new is:—

1. In hydraulic installations including an intake and a head gate of the pivot or butterfly type, a connection between the parts of the gate at opposite sides of the pivot and near the outer edges of the gate, said connection including a sprocket chain, a sprocket wheel over which the chain passes, and means for rotating the wheel to open or close the gate.

2. In hydraulic installations including an intake and a head gate of the pivot or butterfly type, a connection between the parts of the gate at opposite sides of the pivot and near the outer edges of the gate, said connection including a sprocket chain, a sprocket wheel over which the chain passes, means for rotating the wheel to open or close the gate, and manually operated means for moving the sprocket wheel normally disconnected therefrom, and having means enabling connection therewith.

3. In hydraulic installations including an intake and a head gate of the pivot or butterfly type, a connection between the parts of the gate at opposite sides of the pivot and near the outer edges of the gate, said connection including a sprocket chain, a sprocket wheel over which the chain passes, means for rotating the wheel to open or close the gate, and a turnbuckle interposed in the connection.

4. In hydraulic installations including an intake and a head gate of the pivot or butterfly type, a connection between the parts of the

gate at opposite sides of the pivot and near the outer edges of the gate, said connection including a sprocket chain, a sprocket wheel over which the chain passes, a motor for driving the sprocket wheel, a worm gear connection between the motor and the wheel, and means to connect said worm gear connection with the wheel or to disconnect it therefrom.

5. In hydraulic installations including an intake and a head gate of the pivot or butterfly type, a connection between the parts of the gate at opposite sides of the pivot and near the outer edges of the gate, said connection including a sprocket chain, a sprocket wheel over which the chain passes, means for rotating the wheel to open or close the gate, said means including an electric motor, limit switches for stopping the motor at the end of the travel of the gate in each direction, and 10 means driven by the sprocket wheel for operating the limit switches.

6. In hydraulic installations, including an intake and a plurality of head gates for controlling the intake, each of the butterfly type 25 and arranged with their axes in alinement, a common means for operating the gates to open and closed position, connections between the operating means and the several gates, and means to vary the length of either of said 30 connections to cause one of the gates to open in advance of the other.

7. In hydraulic installations, including an intake and a plurality of head gates for controlling the intake, each of the butterfly type 35 and arranged with their axes in alinement, a common means for operating the gates to open and closed position, connections between the operating means and the several gates, means to vary the length of either of said 40 connections to cause one of the gates to open in advance of the other, the operating means including a sprocket wheel and the connection between each gate and the wheel extending from the gate at one side of the pivotal connection around the wheel to a connection with the gate at the other side of the pivotal connection, and including a sprocket chain engaging the wheel.

8. In hydraulic installations, including an 50 intake and a plurality of head gates for controlling the intake, each of the butterfly type and arranged with their axes in alinement, a common means for operating the gates to open and closed position, connections between the operating means and the several gates, means to vary the length of either of said 55 connections to cause one of the gates to open in advance of the other, and means to connect the operating means with either gate 60 or to disconnect it therefrom.

9. In hydraulic installations, including an intake and a plurality of head gates for controlling the intake, each of the butterfly type and arranged with their axes in alinement, a 65 common means for operating the gates to

open and closed position, connections between the operating means and the several gates, means to vary the length of either of said connections to cause one of the gates to open in advance of the other, said common means including an electric motor, limit switches in connection with each gate for stopping the motor, and means whereby each connection may operate the limit switches to stop the motor at the end of the travel of the gate in each direction.

10. In hydraulic installations, including an intake and a plurality of head gates for controlling the intake, each of the butterfly type and arranged with their axes in alinement, a common means for operating the gates to open and closed position, connections between the operating means and the several gates, means to vary the length of either of said connections to cause one of the gates to open in advance of the other, said common means including an electric motor, limit switches in connection with each gate for stopping the motor, and means whereby each connection may operate the limit switches to stop the motor at the end of the travel of the gate in each direction, the limit switches of the gates arranged in parallel so that the movement of either gate may control the stopping of the motor.

11. In hydraulic installations, including an intake and a plurality of head gates for controlling the intake, each of the butterfly type and arranged with their axes in alinement, a common means for operating the gates to open and closed position, connections between the operating means and the several gates, and means to vary the length of either of said connections to cause one of the gates to open in advance of the other, said connections being near the adjacent sides of the gates.

12. In hydraulic installations including an intake and a head gate of the pivot type, a wheel for moving the gate, a flexible member passing about the wheel and having a positive connection therewith to constrain the member to move with the wheel, connections between the ends of the flexible member and the face of the gate at opposite sides of the pivot, and means to rotate the wheel to open or close the gate.

13. In hydraulic installations including an intake and a head gate of the pivot type, a wheel for moving the gate, a flexible member passing about the wheel and having a positive connection therewith to constrain the member to move with the wheel, connections between the ends of the flexible member and the face of the gate at opposite sides of the pivot, and means to rotate the wheel to open or close the gate, one of said connections being variable in length.

14. In hydraulic installations including an intake and a plurality of head gates for con-

trolling the intake, each of the pivot type and arranged with their axes in alinement, a wheel for operating each gate, a flexible member engaging the wheel and having a 5 positive connection therewith to constrain said member to move with the wheel, connections between each flexible member and the adjacent face of the adjacent gate at opposite sides of the pivot, and a common means to rotate the wheels, said means releasable at 10 will from either wheel.

15. In hydraulic installations including an intake and a plurality of head gates for controlling the intake, each of the pivot type and arranged with their axes in alinement, a wheel for operating each gate, a flexible member engaging the wheel and having a 15 positive connection therewith to constrain said member to move with the wheel, connections between each flexible member and the adjacent face of the adjacent gate at opposite sides of the pivot, and a common means to rotate the wheels, said means releasable at 20 will from either wheel, one of said connections at each gate being variable in length for 25 the purpose specified.

16. An hydraulic installation, including an intake, a head gate of the butterfly type for controlling the intake, a motor for operating the gate to opened and closed position, manually operated means for moving the gate, a clutch for connecting the gate to the motor and the manually operated means, and means independent of the clutch to support 35 the gate in partially open position, thereby to facilitate release of the clutch.

17. An hydraulic installation, including an intake, a head gate of the butterfly type for controlling the intake, a shaft connected with 40 the gate for opening and closing the same when the shaft is turned, manually operated means for turning the shaft, a motor for operating the shaft, a clutch between the shaft and the motor, and means to prevent 45 rotation of the shaft under the pull of the gate movable into and out of operative position and cooperating with the manually operated means to release the pressure on the clutch, thereby to facilitate release of the 50 same.

Signed at Charlotte in the county of Mecklenburg and State of North Carolina this 30th day of June A. D. 1927.
